US00D577960S

(12) **United States Design Patent**
Ersan

(10) **Patent No.:** **US D577,960 S**
(45) **Date of Patent:** **** Oct. 7, 2008**

(54) **FOOD SERVING COMBINATION**

(75) Inventor: **Ali Ersan**, Southbank (AU)

(73) Assignee: **Bellett Leasing Pty Ltd** (AU)

(**) Term: **14 Years**

(21) Appl. No.: **29/263,527**

(22) Filed: **Jul. 25, 2006**

(30) **Foreign Application Priority Data**

Feb. 13, 2006 (AU) 10520/06

(51) **LOC (8) Cl.** **07-01**

(52) **U.S. Cl.** **D7/541; D7/538**
